LATCH FOR VEHICLE DOORS

Filed June 10, 1925

Inventor:

24 Rollo Marple,
39 Glendale, Parker & Carlson,
Attns.

UNITED STATES PATENT OFFICE

ROLLO MARPLE, OF CHARLOTTE, MICHIGAN, ASSIGNOR TO HANCOCK MANUFACTURING CO., OF CHARLOTTE, MICHIGAN, A CORPORATION OF MICHIGAN

LATCH FOR VEHICLE DOORS

Application filed June 10, 1925. Serial No. 36,092.

The present invention relates to improvements in latches for vehicle doors, and has particular reference to latches of the type which may be actuated from the outside or inside of the vehicle, and which may be locked from the inside against being actuated from the outside, so that the occupant of a closed vehicle may lock the latches of all doors except one from the inside and then lock the 10 remaining door after leaving the vehicle by means of the usual lock and key.

The primary object of the invention is to provide a new and improved latch of the above type which is simple, inexpensive, and 15 capable of easy and certain operation.

A further object is to provide a novel door latch in which a single means is provided for actuating the latch from the inside and for actuating the locking means adapted to 20 prevent opening of the door from the outside of the vehicle.

A more specific object is to provide a new and improved latch having two operating means in which the locking means is adapted 25 to be operated by one of the operating means, and coacts with the roll-back instead of the latch, thereby permitting the latch to move at all times so as to prevent jarring and breaking of glass when the door is slammed.

30 Further objects and advantages will become apparent as the description proceeds.

In the accompanying drawings, Figure 1 is an inside view in elevation of a latch constructed according to my invention.

35 Fig. 2 is a sectional view taken along line 2-2 of Fig. 1.

Fig. 3 is a view similar to Fig. 1, but with the cover plate removed.

40 Fig. 4 is a sectional view taken along line 4-4 of Fig. 3.

While the invention is susceptible of various modifications and alternative constructions, I have shown in the drawings and will herein describe in detail the preferred embodiment, but it is to be understood that I do not thereby intend to limit the invention to the specific form disclosed but intend to cover all modifications and alternative constructions falling within the spirit and scope 50 of the invention.

Referring to the exemplary embodiment of the invention shown in the drawings, the latch mechanism is mounted in a casing which comprises a base plate 5 having an end flange 6, and a cover plate 7 removably secured in any suitable manner to the base plate. In the present instance, the cover plate 7 is U-shaped in form, and is supported in spaced relation to the base plate 5 by means of end lugs 8 formed on its legs and extending through 55 slots 9 in the flange 6, and of tapped projections 10 on the base plate to which it is secured by screws 11. The casing is adapted to be mounted in a recess formed in the inner face of the vehicle door (not shown).

Slidably mounted on the inside face of the base plate 5 is a latch 12, the nose of which projects through the flange 6. The inner end of the latch 12 is disposed between and adapted to be guided by a pair of lugs 13 struck 60 in from the base plate 5. A coil spring 14 is mounted on one of two lugs 15 struck in from opposite sides of the base plate. The free end of the spring 14 engages the inner end of the latch 12, and tends to move the latter outwardly through the flange 6.

A roll-back 16 is pivotally mounted on one of two studs 17 supported by the base plate at opposite sides of the latch 12, and is adapted to move the latter inwardly against the 70 force of the spring 14. In the present instance, the body of the latch 12 is constructed of two strips 18 rigidly secured together in overlapping relation to provide a space 19 between the base plate and the latch, and an 75 abutment 20 for the roll-back 16. A dog 21 is mounted on a hub 22 rotatably supported in an opening 23 in the base plate 5, and is adapted to actuate the roll-back 16. The hub 22 is adapted to receive the squared shaft 80 of a handle on the outside of the door (not shown). A lug 24 on the dog 21 normally engages the inside of the flange 6, and thereby limits the outward movement of the latch 12.

To positively lock the latch 12 against inward movement by means of the outer handle on the door, a dog 25 is pivotally mounted on a pin 26 on the base plate 5. The dog 25 is provided with a lug 27 adapted to be moved 85

into and out of engagement with a stop lug 28 on the roll-back 16. A leaf spring 29 movable with the dog 25 is adapted to selectively engage a plurality of depressions 30 formed in the base plate 5 to yieldingly hold the dog in adjusted position.

The dog 25 is adapted to be actuated by a vertically arranged rotary spindle 31 provided with a handle 32 for actuating the latch 12 from the inside of the door. An arm 33 formed on the dog 25 extends between two pins 34 on the spindle 31 for all positions of rotation of the latter, and is adapted to be oscillated upon shifting the latter longitudinally, to rock the lug 27 into and out of locking engagement with the lug 28.

The spindle 31 is slidable and rotatably mounted between two pairs of lugs 35 struck in from opposite sides of the base plate 5. The portion of the spindle 31 between these pairs of lugs 35 is bent into the form of a crank which engages a lug 36 struck in from the end of the inner strip 18. The arms of the cover plate 7 serve to confine the spindle 31 between the lugs 35, and are cut away at 37 to provide a space permitting movement of the crank portion and the lug 36. Rotation of the spindle 31 in a clockwise direction will cause an inward movement of the latch 12 independent of any movement of the roll-back 16. A coil spring 38 wound on the spindle 31 tends to rotate the latter in a counterclockwise direction.

The upper edge of the cover plate 7 is cut away to provide an inclined cam surface 39 which engages the lower pin 34 when the spindle is depressed to move the dog 25 into locking engagement with the roll-back 16. Upon rotation of the spindle 31 to unlatch the door, the lower pin 34 will ride along the cam surface 39, thereby shifting the spindle 31 upwardly to unlock the roll-back 16.

It will be evident that I have provided a new and improved latch which can be operated from the inside or the outside of the door, and which can be locked by shifting the operating means on the inside of the door to prevent operating the latch from the outside of the door. By simply actuating the operating means on the inside of the door, the latch will be automatically unlocked. The construction in general is simple, inexpensive, and capable of easy and sure operation. A single means is provided for actuating the latch and for locking the roll-back from the interior of the vehicle. The latch can be moved though locked against actuation from the outside, thereby preventing jars and breaking of glass when the door is slammed.

I claim as my invention:

1. A latch for vehicle doors having, in combination, a casing, a latch in said casing, a spring means for moving said latch outwardly, a roll-back for moving said latch in-

wardly, a rotary spindle for moving said latch inwardly, said spindle being mounted for longitudinal movement, a pair of pins on said spindle, a locking member extending between said pins and being adapted to be oscillated by shifting said spindle, said locking member upon being oscillated being movable into or out of locking engagement with said roll-back, and cam means formed on said casing for engaging one of said pins to shift said spindle longitudinally to disengage said locking means and said roll-back upon rotation of said spindle.

2. A latch for vehicle doors having, in combination, a base plate, a latch, spring means for moving said latch outwardly, a rotary spindle having means engaging said latch for moving the latter inwardly against the force of said spring, spaced lugs struck in from said base plate, said spindle being journaled at spaced points between said lugs, and a cover plate fitting over said lugs to retain said spindle therein.

3. A latch for vehicle doors having, in combination, a base plate, a latch movable on said base plate, spring means for moving said latch outwardly, a rotary sliding spindle having a crank portion engaging the latch for moving the latter inwardly against the force of said spring, two pairs of lugs struck in from said base plate at opposite sides of said crank portion, said spindle being journaled between said lugs and said pairs of lugs being spaced sufficiently apart to permit sliding movement of said crank portion, and a cover plate fitting over said lugs to retain said spindle therein.

4. In a lock, in combination, a rotary slideable spindle, a pivotal dog operated by said spindle, said dog having an arm extending alongside the spindle whereby to permit rotation of the spindle independently of the position of the dog, and means projecting from the spindle to engage said arm whereby to move the dog on sliding the spindle.

5. In a lock, in combination, a rotary slideable spindle, a pivotal dog operated by said spindle, said dog having an arm extending alongside the spindle whereby to permit rotation of the spindle independently of the position of the dog, means projecting from the spindle to engage said arm whereby to move the dog on sliding the spindle, and a cam means arranged to slide the spindle on rotation thereof.

In testimony whereof, I have hereunto affixed my signature.

ROLLO MARPLE.
